PARKING METER BOX DISPLAY

Curtis M. Williams, Phoenix, Ariz.

Application July 18, 1945, Serial No. 605,707

1 Claim. (Cl. 40—7)

1

This invention relates to parking meter boxes, and has for its objects:

First, the provision of a parking meter box, having signal viewing windows and an access door provided with a rounded top having a transparent plastic top with a recess beneath it to receive a printed card or paper bearing indicia;

A second object is to provide a parking meter box having an access door with a top having a recessed portion inlaid with a transparent plate, together with a recess beneath said transparent plate adapted to receive printed cards, or the like, in a manner so that they can be easily removed and changed when said access door is open, and all parts will be closed weatherproof when said access door is closed.

Other objects will appear hereinafter.

I attain the foregoing objects by means of the structure shown in the accompanying drawings, in which—

Figure 1 is an elevational cross section of my improved meter box;

Figure 2, a front elevation thereof;

Figure 3, a plan view thereof;

Figure 4, a perspective view of the transparent top;

Figure 5, a transverse section of the box taken substantially on line 5—5, Figure 3; and

Figure 6 is a section of a fragment of the upper left corner of the meter box.

Similar numerals refer to similar parts in the several views.

The box body 2 is made of two mating parts 3 and 4, which join along line 5 on their abutting outer edges, and are held together by screws 6.

One box part has a viewing window 7 and the other part has an access door 8, held closed by lugs 10 and a lock 11. The case thus formed has rounded edges, an attaching boss 12, and a top 14, which is rounded from front to rear, and smoothly rounded near the side edges.

The middle portion of the top of the composite box is provided with a transversely extending recess 15. The back wall and end walls, 17 and 18 of this recess, are provided with shoulders 19 having grooves 20 to receive the rimmed edges of the transparent top 23. The transparent top plate 23 has a depending lip 24 formed along the back edge 25 and lateral edges 26 sized to fit into groove 20 on the shoulders 19 formed in the material of the top of the case. The front edge 28 of the top, however, has no depending lip but is grooved along the top edge to form a horizontally protruding lip 29.

The access door 8 is fitted, and fastened, to the

case part according to the customary practice and structure known to the art. However, the inner face just below the upper edge of the door is provided with a groove 30 positioned to receive the lip 29 of the top 23. This groove is somewhat deeper than lip 29 and a gasket of soft rubber 31 is placed in its bottom. When the top 23 is in place, a slotted cavity 33 is formed between the upper face of the case parts within the recess area and the lower face of the top. This cavity has substantially the same depth as the height of shoulders 19 and is bounded on the back and sides by them, but is open in the front, when the access door is removed, so that a card 34, bearing any printed or written material desired 35, may be inserted or removed.

The top 23 is preferably made of transparent thermoplastic material formed and molded to the shape shown. However, the several lips may be molded or machined as desired.

In assembling the box, the two castings are first fastened together. A cement, adapted to form a bond between these metal parts and top 23, is then spread on shoulders 19 and the top pressed in place until the cement sets.

The meter clock and coin-actuated apparatus is then inserted in the usual manner and a card bearing operating directions, or advertising material, is inserted in the cavity beneath the top. The access door is then set in place and drawn to closed position by screws 36.

I am fully aware that parking meter case parts, with access doors and coin-operated clocks are well known to the art and make no claims to this structure. However, in addition to the usual structure, I have provided a case with a transparent top which forms a weatherproof top cover and also encloses a cavity into which a card may be inserted when the access door is opened.

The card is easily viewed through this transparent top and is in the most visible position on the box. The top 23 also forms an effective seal and weatherproof closure for the top of the case, thus protecting the interior mechanism. The card may be removed only when the access door is opened. Since this may be fully opened only by use of the lock, as is well known to those familiar with the art, the card cannot be tampered with by any unauthorized person.

Since the structure is subject to wide variation and to substitution of mechanically equivalent parts, I wish to be limited only by the following claims.

I claim:

A parking meter box having an access door and a rounded top with a recess formed therein

3

extending transversely throughout a substantial part thereof, a shoulder formed along the side edges and rear edge opposite said access door of said recess, said shoulder having a groove adjacent the walls of said recess, a groove extending transversely of said access door along the inner face thereof below its top edge, a top of transparent material having a depending lip along its back and side edges adapted to fit into said grooves on said recess shoulders, and a horizontally extending lip on the lower part of its front edge, a cavity adapted to receive a card formed in said recess between the case body and said transparent top, said top adapted to conform to the contour of the top of said box with its side and back edges resting on and attached to said shoulders and its depending lip engaging in said shoulder grooves; said access door having a groove fitted with a gasket extending along its inner

face below its top edge adapted to receive the horizontal lip of said top in water-tight relation when said door is in closed position.

CURTIS M. WILLIAMS.
